UNITED STATES PATENT OFFICE

2,522,711

VENT FOR PUMPS

Charles W. Ginter, Bryan, Ohio, assignor to The Aro Equipment Corporation, Bryan, Ohio, a corporation of Ohio

Application July 9, 1947, Serial No. 759,741

13 Claims. (Cl. 103—203)

1

This invention relates to a vent for a pump for pumping liquid, such as lubricating oil, and more particularly to such pumps for use in conjunction with a device for metering or measuring the amount of liquid pumped.

It is an object of the invention to remove substantially all the air or other gases from the liquid to be pumped through the meter, so that only liquid is measured on the meter. This is particularly important because the amount for the liquid dispensed is paid for by a customer depending on the meter reading, and accuracy is essential.

It is another object of the invention to provide an improved vent for a liquid pump which functions to prevent pumping of air or gas when the supply in the container from which the fluid is pumped gets low.

It is also an object of the invention to return any air or gas which passes the foot valve of a fluid pump to the liquid below the foot valve and outside the confines of the pump.

It is a further object of the invention to provide an air or gas vent for a fluid pump in which the air or gas is vented through a hollow tube extending from and through the piston valve stem to a position below the foot valve.

It is another object of the invention to provide a valve stem in the form of a hollow rod which is of novel notched design to permit the passage of air and some oil therethrough if air passes into the pump chamber above the foot valve.

With these and other objects in view, the invention consists in the construction, arrangement and combination of the various parts of my device whereby the objects contemplated are attained, as hereinafter more fully set forth, pointed out in the claims and illustrated in the accompanying drawings, wherein:

Figure 1 is a vertical sectional view of the lower portion of a lubricant pump.

Figure 2 is a partial vertical sectional view of the lubricant pump piston valve stem and hollow air vent tube, taken with the same parts shown in Figure 1 rotated 90° about their vertical axis.

Figure 3 is a horizontal sectional view taken on line 3—3 of Figure 1;

Figure 4 is a horizontal sectional view taken on line 4—4 of Figure 1;

Figure 5 is a section view taken on line 5—5 of Figure 2; and

Figure 6 is a sectional view of a hollow valve stem and hollow tube assembly illustrating another embodiment of the invention.

Figure 7 is a partial sectional view of the device shown in Figure 6 with the same parts with some parts shown in elevation instead of in section and with the piston in an upper position;

Figure 8 is a horizontal sectional view taken on line 8—8 of Figure 6;

2

Figure 9 is a vertical sectional view of a third embodiment of the invention; and

Figure 10 is a sectional view taken on line 10—10 of Figure 9.

Referring specifically to Figures 1 to 5, inclusive, for a detailed description of the first embodiment of the invention, numeral 20 designates a cylinder for the pump having a foot valve, generally indicated at 21 at the bottom thereof. The foot valve 21 extends into the liquid to be pumped from a liquid container 19 and is positioned adjacent the bottom thereof. The foot valve 21 comprises a relatively heavy valve plate 23 which seats by gravity on a valve seat 22.

A piston generally indicated at 24 reciprocates in the cylinder 20 and includes an upper portion 25 which is connected to a suitable reciprocating piston rod 45. The piston 24 divides the cylinder into an upper pressure chamber 26 and a lower inlet chamber 27. A chamber 28 is formed below the foot valve plate 23.

A vertically extending generally cylindrical rod 29 is slidably mounted on the foot valve plate at 30 and extends therethrough so that a portion is positioned in the chamber 28 below the foot valve plate 23 and the major portion is positioned in the chamber 27 above the foot valve plate 23 when the piston 24 is in its upper position, as shown in Figures 1 and 2. The rod 29 is provided with a central bore 31 extending throughout its length and with a flat 32 which extends from the top of the rod to a point just above the valve plate 23.

An open chamber 33 is provided centrally of the lower part of the piston 24 and suitable packing 34 of leather or the like insures that piston 24 will prevent the leakage of liquid around the outside of the piston.

A piston valve plate 35 is provided in the piston 24 and is biased toward a piston valve seat 37 by a compression spring 36. The piston valve plate 35 is secured to a piston valve stem 38 which is hollow and forms a closed chamber 39, with the hollow portion of the piston 24 which forms a chamber 41 communicating with chamber 39. It is understood that the piston rod 45 is secured to the upper portion 25 of piston 24 in a fluid tight manner. Portion 25 is also provided with an internal shoulder 40 to limit the upward movement of valve stem 38.

The piston 24 has a web 42 connecting the piston portion and the upper portion 25 thereof through threads 44, which web is open to upper cylinder chamber 26, as is apparent from the drawing. It is to be noted that the piston valve plate 35 is provided with a central aperture 43 through which the hollow rod 29 extends with considerable clearance.

Referring now to Figures 6, 7 and 8 for a detailed description of a second embodiment of the

invention, numeral 51 designates a cylinder having a foot valve generally indicated at 52 disposed adjacent the bottom thereof. The cylinder and foot valve are adapted to be inserted in a container, such as shown at 19 in Figure 1, and to extend almost to the bottom thereof, as shown in that figure. A piston generally indicated at 53 divides the cylinder 51 into an upper pressure chamber 54 and a lower inlet chamber 55, it being noted that the piston 53 is shown in a lower position in Figure 6 and in an upper position in Figure 7.

The foot valve comprises a relatively heavy valve plate 56 seated by gravity on a seat 57. A chamber 58 is formed by the casting forming the valve seat below the foot valve plate 56.

The piston 53 comprises a main piston member 59 including suitable packing 61, which main piston 59 is secured to a hollow casting 62 which forms an open chamber 63 communicating with chamber 55 and also provides a valve seat 64 for an annular piston valve member 65. The piston valve member 65 is biased toward its seat by a compression spring 66. An elongated casting 68 is secured to the hollow seat casting 62 by cooperating threads 69 at one end thereof, and is secured to a reciprocating piston rod 71 by cooperating threads 72 at the other end thereof. The casting 68 is hollow and provides an elongated chamber 73 therein, which chamber is open at its lower portion and communicates with pressure chamber 54 by reason of apertures 74 in the casting and webs 75 which connect with the piston valve seat member 62 and form the lower portion of casting 68.

The piston rod 71 extends through an upper cylinder casting 76 and connects to suitable reciprocating mechanism (not shown). An outlet passage 77 for the fluid pumped is provided in the upper cylinder casting 76 and a packing 78 surrounds the piston rod 71.

A hollow piston valve stem 79 is connected to the piston valve member 65 and reciprocates therewith within the chamber 73. A plug 81 is secured to the top of the valve stem 79 in a fluid tight manner and provides a closed compartment or chamber 82.

A rod 83 extends downwardly through the foot valve plate 56 into the chamber 58 and is preferably slidably mounted on the foot valve plate. The rod 83 extends upwardly through the hollow casting 62, and into the chamber 82 formed by the valve stem 79. The rod is provided with a bore 84 throughout its length and an elongated slot or notch 85 is cut in its upper portion. Furthermore, the external diameter of the rod 83 is somewhat smaller than the internal diameter of the valve stem 79, providing a clearance space therebetween indicated at 86. Obviously, the valve stem 79 and the hollow rod 83 are reciprocable relative to each other, without interference.

Referring specifically to Figures 9 and 10 for a detailed description of the third embodiment of the invention, a similar type pump is shown for disposition in a closed vessel 91 containing liquid to be pumped, and numeral 92 designates a cylinder having a foot valve 93 seated at 94 on a member 95 at the bottom of the cylinder 92. The cylinder 92 is adapted to extend into the container 91 adjacent the bottom thereof.

A piston generally indicated at 96 divides the cylinder 92 into an upper pressure chamber 97 and a lower inlet chamber 98. A chamber 99 is formed by member 95 beneath the valve seat and ports 101 are formed in member 95.

The piston 96 comprises a main piston member 102 including suitable packing 103, which main piston member is secured to a hollow seat casting 104 forming an opening 105 communicating with inlet chamber 98 and also providing a valve seat 106 for an annular piston valve member 107. The piston valve member 107 is biased toward its seat 106 by a relatively strong compression spring 108. An elongated casting 109 is secured to the seat casting 104 by screw threads 111. The casting 109 is open at its bottom and provides an elongated chamber 112 therein communicating with pressure chamber 97 by reason of openings 113 in the casting 109. A piston rod 114 extends through an upper cylinder casting 115 and connects to a suitable manual, mechanical or electrical reciprocating mechanism (not shown). Suitable outlet passages and a meter, such as shown at 90 in Figure 7, are also provided, but are not shown.

A hollow piston valve stem 116 is connected to the piston valve member 107 and reciprocates therewith in chamber 112. A plug 117 closes the top of the valve stem 116 in a fluid tight manner and provides a chamber 118. It is to be noted that chamber 118 is in substantially free and open communication with passageway 105 in casting 104 and with the inlet chamber 98 in cylinder 92.

A hollow rod 119 extends downwardly through the foot valve plate 95 into the chamber 99 and is preferably slidably mounted on the foot valve plate 95. The rod 119 also extends upwardly through chamber 98, hollow casting 104 and into chamber 118 formed by the valve stem 116. The rod 119 is spaced a considerable distance from the piston valve 107, seat 106 and piston valve stem 116. The rod 119 is provided with a hollow bore 121. Obviously, the valve stem 116 and the hollow rod 119 are reciprocable relative to each other without interference.

Operation of Figures 1 to 5

Assuming that the liquid level in the container 19 is at the position shown in Figure 1, and the piston rod 45 is being reciprocated, the piston 24 will move upwardly to force liquid under pressure from upper chamber 26, at the same time causing a reduction in pressure in lower chamber 27. The foot valve plate 23 will, therefore, be raised from its seat 22 and liquid will enter chamber 27 from container 19 through ports 22a in the foot valve.

When the piston 24 is moved downwardly, the foot valve plate 23 is closed and the piston valve member 35 is lifted from its seat 37 against the bias of spring 36, whereupon liquid from chamber 27 passes through chamber 33, past the piston valve member 35, through the openings between web 42 and into chamber 26. Obviously, when the piston 24 begins its upward movement, the piston valve member 35 is again seated and liquid is prevented from flowing between chambers 26 and 27.

During the downward stroke of piston 24, some liquid will pass from the lower chamber 27, through the aperture 43 in the piston valve member 35, past the flat portion 32 of rod 29, into chamber 33 and thence downwardly through the bore 32 of rod 29 and back to the container 19. However, due to the relative restriction between the parts, only a small amount of liquid compared to the amount pumped will be returned to the drum or container 19 through the rod 29.

When the liquid in the drum has lowered to the lower end of the pump, that is, below the foot

valve 21, air will enter the chamber 27 when the foot valve plate 23 lifts. As the piston reciprocates, this air will be compressed slightly and will pass from chamber 27, through aperture 43 in piston valve member 35, past the flat portion 32 of rod 29, into chamber 39 and thence downwardly through the bore 32 of rod 29 and back to container 19.

The piston valve spring 36 will prevent the piston valve member 35 from opening, as the pressure exerted against the piston valve member 35 is very slight when air is present in chamber 27. Thus, the air which enters chamber 27 cannot pass into chamber 26 from whence it would pass through the measuring meter (not shown). Only liquid pumped is, therefore, registered on the meter. It will be apparent that no air which passes into the chamber 39 may enter pressure chamber 26 because the two chambers are sealed from each other.

Operation of Figures 6 to 8

The operation of the pump is exactly the same in the embodiment shown in Figures 6 to 8 as described with respect to Figures 1 to 5. On the upward stroke of piston 59, the liquid from chamber 54 is forced outwardly under pressure through passageway 71 to a meter 90. The foot valve plate 56 is raised from seat 57 and liquid from container 19 enters the chamber 55 through ports 60. Piston valve member 65 is closed.

On the downward stroke of the piston 59, foot valve plate 56 is closed and piston valve member 65 is opened, thereby affording passage of the liquid from the lower chamber 55, through chamber 63, past the piston valve member 65 and through openings 74 into upper chamber 54. Slight amounts of the liquid pumped will pass through clearance 86 between the rod 83 and valve stem 79 and into the bore 84 through slot 85, thence downwardly in the bore to below the foot valve and into container 19. The amount of liquid pumped back to container 19 will be small, however, due to the relative restriction between the parts of the pump.

When the liquid level in the container 19 falls below the foot valve 52, air will enter the chamber 55 when the foot valve plate 56 opens. The air will be under slight pressure as the piston 59 reciprocates, but the pressure will not be sufficient to lift the piston valve member 65 against the bias of the valve spring 66. Air from chamber 55, therefore, passes through the clearance 86 between the rod 83 and the valve stem 79 and enters the chamber 82, passes through notch 85 and downwardly through bore 84 of rod 83 to container 19. Any air which enters chamber 82 cannot enter pressure chamber 54 since these chambers are sealed from each other. Therefore, no air may pass through outlet passage 71 and register on the meter 90.

Operation of Figures 9 and 10

The operation of the pump per se is exactly the same in Figures 9 and 10 as described with respect to the other figures. On the upward stroke of piston 96, the lubricant or liquid from the pressure chamber 97 is forced out of the pump and the foot valve plate 93 is raised from seat 94 so that liquid from the container 91 enters chamber 98 through the ports 101. Piston valve member 107 is closed on its seat 106.

On the downward stroke of the piston 96, the foot valve plate 93 is closed and piston valve 107 is opened, thereby affording passage of liquid from

the inlet chamber 98, through passage 105, past the piston valve member 107, and through the openings 113 in casting 109 into the upper chamber 97.

When the lubricant level in the container reaches the lower chamber 99 below the foot valve, air will be pumped into inlet chamber 98. Elimination of the air is accomplished because the heavy spring 108 does not permit the piston valve 107 to open when air is present, but the piston itself forces the air back through the bore 121 of the rod 119 to the container 91, whereupon it rises to the top of the liquid therein. Since the chamber 118 formed by the piston valve stem 116 and plug 117 is sealed from the chamber 97, no air may be pumped and only liquid will register on the measuring meter.

Although there is a slight loss in efficiency in the pumping operation due to some lubricant being returned through bore 121 on each stroke, even when no air is present, it is more important to insure that only lubricant substantially free of air passes through the measuring meter.

It is to be noted that in all the embodiments shown, the passage between the cylinder inlet chamber and the container, including the passage through the vent rod, is relatively restricted compared with the passage through the piston valves through which the majority of the lubricant passes.

From the foregoing it will be apparent that I have provided improved pump construction which insures that liquid only will be pumped and registered on the measuring meter of apparatus of the type described.

Some changes may be made in the construction and arrangement of the parts of my vent for pump without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slideable hollow valve stem for said piston valve having its hollow portion isolated from said chamber above said piston valve, a rod having one end extending through said foot valve into the liquid to be pumped and having its other end extending into the hollow portion of said valve stem, means providing communication between said hollow portion of the valve stem and the portion of the cylinder below said piston valve, means providing communication between said hollow portion of said valve stem and the liquid below the foot valve, and an outlet from said pump.

2. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slideable hollow valve stem for said piston valve having its hol-

low portion isolated from said chamber above said piston valve, a rod having one end extending through said foot valve into the liquid to be pumped and having its other end extending into the hollow portion of said valve stem, means providing communication between said hollow portion of the valve stem and the portion of the cylinder below said piston valve, said rod being hollow to provide communication between said hollow portion of the valve stem and the liquid below the foot valve, and an outlet from said pump.

3. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slidable hollow valve stem for said piston valve having its hollow portion isolated from said chamber above said piston valve, a rod having one end extending through said foot valve into the liquid to be pumped and having its other end extending into the hollow portion of said valve stem, said rod including means providing communication between said hollow portion in the valve stem and said chamber of the cylinder below the said piston valve, means providing communication between said hollow portion of said valve stem and the liquid below said foot valve, and an outlet from said pump.

4. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slidably hollow valve stem for said piston valve having its hollow portion isolated from said chamber above said piston valve, a rod having one end extending through said foot valve into the liquid to be pumped and having its other end extending into the hollow portion of said valve stem, said rod including means providing communication between said hollow portion in the valve stem and said chamber of the cylinder below the said piston valve, said rod being hollow to provide communication between said hollow portion of the valve stem and the liquid below the foot valve, and an outlet from said pump.

5. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slideable hollow valve stem for said piston valve having its hollow portion isolated from said chamber above said piston valve, a rod having one end extending through said foot valve into the liquid to be pumped and having its other end extending into the hollow portion of said valve stem, said rod including a reduced portion providing communication between said hollow portion in the valve stem and said chamber of the cylinder below said piston valve, means providing communication between

said hollow portion of said valve stem and the liquid below the foot valve, and an outlet from said pump.

6. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston 10 valve and a variable chamber above said piston valve, means for biasing said piston valve in one direction in said piston, a slid able hollow valve stem for said piston valve having its hollow portion isolated from said chamber above said piston 15 valve, a rod having one end extending through said foot valve into the liquid to be pumped and having its other end extending into the hollow portion of said valve stem, said rod including a flat portion providing communication between 20 said hollow portion in the valve stem and said chamber of the cylinder below said valve, means providing communication between said hollow portion of said valve stem and the liquid below the foot valve, and an outlet from said pump.

25 7. A liquid pump comprising a cylinder adapted
to extend at least partially into said liquid, a foot
valve at the inlet portion of the cylinder, a piston
reciprocable in said cylinder, means for recipro-
cating said piston, a valve carried by said piston
30 defining a variable chamber below said piston
valve and a variable chamber above said piston
valve, means for biasing said piston valve in one
direction in said piston, a slidably hollow valve
stem for said piston valve having its hollow por-
35 tion isolated from said chamber above said piston
valve, a rod having one end extending through
said foot valve into the liquid to be pumped and
having its other end extending into the hollow
portion of said valve stem, means providing com-
40 munication between said hollow portion of the
valve stem and the portion of the cylinder below
said piston valve, means providing restricted com-
munication between said hollow portion of said
valve stem and a location below the foot valve,
45 and an outlet from said pump.

8. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slideable hollow valve stem for said piston valve having its hollow portion isolated from said chamber above said piston valve, a rod having one end extending through said foot valve into the liquid to be pumped and having its other end extending into the hollow portion of said valve stem, means providing communication between said hollow portion of the valve stem and the portion of the cylinder below said piston valve, means providing restricted communication between said hollow portion of said valve stem and a location below the foot valve, said last means comprising a rod having a passage therethrough of less cross sectional area than the cross sectional area defined by said piston valve, and an outlet from said pump.

9. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston

valve and a variable chamber above said piston valve, means for biasing said piston valve in one direction in said piston, a slideable hollow valve stem for said piston valve having its hollow portion isolated from said chamber above said piston valve, a rod having one end extending through said foot valve into the liquid to be pumped and having its other end extending into the hollow portion of said valve stem, means providing communication between said hollow portion of the valve stem and the portion of the cylinder below said piston valve, means providing restricted communication between said hollow portion of said valve stem and a location below the foot valve, said last means comprising a rod having a passage therethrough of less cross sectional area than the cross sectional area defined by said piston valve, said rod being spaced a considerable distance from said valve stem and said piston having a relatively large passage centrally thereof communicating with the hollow portion of said valve stem, whereby unrestricted communication is afforded between said chamber below the piston valve and the hollow valve stem, and an outlet from said pump.

10. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slideable hollow valve stem for said piston valve having its hollow portion isolated from said chamber above said piston valve, a rod having one end extending through said foot valve into the liquid to be pumped and having its other end extending into the hollow portion of said valve stem, means providing communication between said hollow portion of the valve stem and the portion of the cylinder below said piston valve, and providing restricted communication between said hollow portion of said valve stem and a location below the foot valve, said last means comprising a rod having a passage therethrough of less cross sectional area than the cross sectional area defined by said piston valve, said rod being spaced a considerable distance from said valve stem and said piston having a relatively large passage centrally thereof communicating with the hollow portion of said valve stem, whereby unrestricted communication is afforded between said chamber below the valve and the hollow valve stem, the interior of said hollow valve stem being sealed off from said chamber above the piston valve, and an outlet from said pump.

11. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slideable hollow valve stem for said piston valve having its hollow portion isolated from said chamber above said piston valve, a rod having one end extending through said foot valve into the liquid to be pumped and having its other end extending into the hollow portion of said valve stem, means providing communication between said hollow portion of the valve stem and the portion of the

cylinder below said piston valve, means providing restricted communication between said hollow portion of said valve stem and a location below the foot valve, said last means comprising a rod having a passage therethrough of less cross sectional area than the cross sectional area defined by said piston valve, said rod being secured to said foot valve, and an outlet from said pump.

12. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slideable hollow valve stem for said piston valve having its hollow portion isolated from said chamber above said piston valve, a rod having one end extending through said foot valve into the liquid to be pumped and having its other end extending into the hollow portion of said valve stem, means providing communication between said hollow portion of the valve stem and the portion of the cylinder below said piston valve, means providing restricted communication between said hollow portion of said valve stem and a location below the foot valve, said last means comprising a rod having a passage therethrough of less cross sectional area than the cross sectional area defined by said piston valve, said rod being spaced a considerable distance from said valve stem and said piston having a relatively large passage centrally thereof communicating with the hollow portion of said valve stem, whereby unrestricted communication is afforded between said chamber below the piston valve and the hollow valve stem, and an outlet from said pump.

13. A liquid pump comprising a cylinder adapted to extend at least partially into said liquid, a foot valve at the inlet portion of the cylinder, a piston reciprocable in said cylinder, means for reciprocating said piston, a valve carried by said piston defining a variable chamber below said piston valve and a variable chamber above said piston valve, means for biasing said piston valve in one direction in said piston, a slideable hollow valve stem for said piston valve having its hollow portion isolated from said chamber above said piston valve, a rod having one end extending through said foot valve into the liquid to be pumped and having its other end extending into the hollow portion of said valve stem, means providing communication between said hollow portion of the valve stem and the portion of the cylinder below said piston valve, means providing restricted communication between said hollow portion of said valve stem and a location below the foot valve, said last means comprising a rod having a passage therethrough of less cross sectional area than the cross sectional area defined by said piston valve, and an opening in the side of the rod communicating with the passage therethrough, and an outlet from said pump.
